CONTAINER WITH ROTATABLE SPOUT

William F. Punte, Syracuse, N. Y., assignor to
 Continental Can Company, Inc., New York,
 N. Y., a corporation of New York

Application August 10, 1935, Serial No. 35,644

6 Claims. (Cl. 221—19)

The present invention relates to new and useful improvements in dispensing containers and more particularly to a metal container having a pouring spout which is movable from a housed position lying within the outer limits of the end seam of the container to a dispensing position wherein it extends above and beyond the said end seam.

An object of the invention is to provide a dispensing container having a raised portion and a metal spout rotatably mounted thereon for movement from a housed position wherein the spout lies substantially flat against the end of the container to a dispensing position wherein the spout extends over and beyond the edge of the end seam of the container.

A further object of the invention is to provide a dispensing container of the above type, wherein inclined raised portions are provided in the container end for forcing the spout upwardly and over the end seam when it is moved to a dispensing position.

A further object of the invention is to provide a container of the above type wherein the end of the raised portion is closed except for a relatively small pouring opening, and wherein the spout is provided with a member overlying said closed end for covering the pouring opening when the spout is turned to a housed position within the limits of the end seam.

A still further object of the invention is to provide a dispensing container of the above type wherein the spout is made of spring metal so that as it is moved to a dispensing position, it will be sprung upwardly to extend over and beyond the end seam, and so that as it is returned to a housed position, it will spring back to lie flat against the end of the container.

The above and other objects will in part be obvious and will in part be hereinafter more fully disclosed.

In the accompanying drawing:

Figure 1 is a top plan view of the dispensing container showing the pouring spout in a closed position.

Figure 2 is a similar view showing the pouring spout in a dispensing position.

Figure 3 is an enlarged sectional view taken along the line 3—3 of Fig. 1.

Figure 4 is an enlarged sectional view taken along the line 4—4 of Fig. 2.

Figure 5 is a fragmentary side view in section showing the raised lugs for forcing the spout portion upwardly.

Figure 6 is a detail view in section showing the

manner in which the pouring spout is placed on the can end before the raised portion is flanged.

Figure 7 is a detail view showing the raised portion after it has been flanged to hold the pouring spout in position.

The invention relates generally to a metal container for dispensing oil or other liquid products. The container ends are secured to the body portion preferably by double seaming. The top end is provided with a raised portion which is formed integrally therewith and serves as a securing means for a dispensing spout. The dispensing spout is provided with a shank portion portion having an opening therethrough fitting over said raised portion. After the shank of the spout is placed over the raised portion, then the raised portion is pressed down to form a flange which projects over the shank of the spout, thus permanently securing the spout to the container end but permitting said spout to be shifted about a vertical axis centrally of the raised portion.

The spout normally lies within the outer limits of the end seam of the container in its housed position. When the spout is turned about the raised portion as an axis, it is urged upwardly so as to pass over the double seam and project beyond the same for dispensing the contents of the container.

There are various ways in which the spout can be urged over the double seam, as for instance by flexing the can end when the spout is turned to a dispensing position, or by forming the spout of spring metal, or by causing the spout to be bent as it is turned to a dispensing position. The raised portion has an opening formed at one side of the center thereof and the shank of the spout has an upwardly projecting member which is bent over the upper end of the raised portion and thus serves as a closing member for closing the opening when the spout is turned to a position so that it is housed beneath the outer limits of the double seam.

When the spout is turned to a position for dispensing the contents, then the closure member uncovers the opening. The container end is provided with raised lugs which incline upwardly and outwardly from the plane of the end toward the double seam, and these raised lugs are disposed adjacent the double seam and serve as a means for

forcing the spout upwardly to cause it to ride over the double seam when it is turned to a position for dispensing.

Referring more in detail to the drawing, the container consists of a body portion 10 having a top end 11 double seamed thereto, as indicated at 12. The container end 11 is provided with a

raised portion 13 (see Fig. 6). This raised portion is formed integral with the end and may be formed by drawing the metal. A spout 15 is secured to this raised portion. The spout is provided with a shank portion 15a which is formed with an opening adapted to freely fit down over the raised portion. After the shank is placed on the raised portion, then the raised portion is pressed downward so as to form a flange 13a which overlies the shank and secures the spout to the container end. The opening in the shank of the spout is so dimensioned that the spout will turn freely on this flanged raised portion and about an axis centrally thereof and perpendicular to the plane of the container end.

In the particular embodiment of the invention, the spout is made of spring metal and normally lies substantially in a plane of the raised portion and in contact with the outer face of the container end 11, as indicated in Fig. 3 of the drawing. Said spout has the side edge portions 18 bent upwardly in order to provide a trough portion for dispensing the liquid contents of the container but these upwardly turned portions do not interfere with the springing of the metal of the spout so that it may be sprung to a position to overlie the double seam.

The container end is provided with raised portions 17 which incline upwardly and outwardly from the plane of the container end toward the double seam. These raised portions are disposed adjacent the double seam and are so dimensioned that when the spout is turned from the position indicated in Fig. 1 either to the right or to the left, it will contact one of the raised portions 17, and this will gradually flex the spout so that it will pass over the double seam and overhang the same, as shown in Fig. 4, for dispensing the liquid contents of the container. When the spout is returned to the position of Fig. 1, it will be released and will spring back into a position substantially in contact with the outer face of the container end and will thus be completely housed within the outer limits of the double seam.

The raised portion which secures the spout to the container end is also completely housed within the outer limits of the double seam, so that when the spout is in closed position, as shown in Figs. 1 and 3, neither the spout nor the projecting portion to which it is attached projects above the limits of the double seam, and therefore containers may be readily stacked one on the other.

The raised portion 13 has an opening 14 formed therethrough which is disposed at one side of the center of the raised portion 13, as clearly shown in the drawing. The shank portion 15a of the spout is bent upwardly and thence over the raised portion, as indicated at 16. This provides a closure member for the opening 14. This closure member is so dimensioned and positioned on the shank of the spout that when the spout is in the position shown in Fig. 1, it overlies the opening and will firmly contact with the outer face of the raised portion so as to seal the opening. When, however, the spout is turned to the position shown in Fig. 2, then this closure member will uncover the opening which is at one side of the center of the raised portion. The opening is preferably on the side of the raised portion adjacent the double seam, and therefore when the spout is turned to the position indicated at Fig. 2, the contents poured from the opening 14 will pass into the spout and be directed by the spout over the double

seam and well away from the side wall of the container.

From the above it will be apparent that a dispensing means has been provided for a container which is very simple in construction and which includes a pouring spout permanently but rotatably attached to the container. This pouring spout also serves as a closure for the container so that when the spout is moved to dispensing position, the container is open and free and the liquid contents may be freely dispensed onto and over the spout. When the spout is moved to its housed position, then the pouring opening is closed and in this position not only the spout but the means which attaches it to the container end are all completely housed within the outer limits of the double seam.

Furthermore, when the spout is attached to the raised portion projecting above the plane of the end, there are no pockets or recesses within the container adjacent the raised portion which will prevent the emptying of the entire contents of the container.

It is obvious that minor changes in the details of construction may be made without departing from the spirit of the invention as set forth in the appended claims.

I claim:

1. A dispensing container comprising a body portion, an end double seamed thereto, said end having a raised portion provided with a dispensing opening in its outer end, a dispensing spout permanently attached to said raised portion for rotation thereon in a fixed position relative thereto, said spout being formed of spring metal and shaped so as to lie housed within the outer limits of the double seam when over and in contact with the container end and so as to spring over the double seam when turned to dispensing position, said container end having raised inclined lugs for forcibly contacting with said spout for springing the same over the double seam when the spout is turned to dispensing position.

2. A dispensing container comprising a body portion, an end double seamed thereto, said end having a raised portion therein with a dispensing opening located in the closed end at one side of the center thereof, a dispensing spout including a shank portion having an opening therethrough adapted to freely fit around said raised portion, said raised portion having an integral flanged head overlying said shank for permanently securing said dispensing spout to said container end, said dispensing spout having a dispensing portion formed of spring metal shaped so that said spout portion lies substantially in contact with the container end when moved to a position completely over the same and so as to spring to permit the spout to move over the double seam to dispensing position.

3. A dispensing container comprising a body portion, an end double seamed thereto, said end having a raised portion therein with a dispensing opening located in the closed end at one side of the center thereof, a dispensing spout including a shank portion having an opening therethrough adapted to freely fit around said raised portion, said raised portion having an integral flanged head overlying said shank for permanently securing said dispensing spout to said container end, said dispensing spout having a dispensing portion formed of spring metal shaped so that said spout portion lies substantially in contact with the container end when moved to a position completely over the same and so as to spring to

5 permit the spout to move over the double seam to dispensing position, said shank portion of the dispensing spout having an upwardly projecting and laterally bent closure member adapted to move over the opening in the end of the raised portion for closing the opening when the dispensing spout is moved to a position over and adjacent the container end, said closure member being movable with the dispensing spout so as to 10 uncover said opening when said spout is in dispensing position.

10 4. A dispensing container comprising a body portion, an end double seamed thereto, said end having a raised portion therein with a dispensing 15 opening located in the closed end at one side of the center thereof, a dispensing spout including a shank portion having an opening therethrough adapted to freely fit around said raised portion, said raised portion having an integral flanged 20 head overlying said shank for permanently securing said dispensing spout to said container end, said dispensing spout having a dispensing portion formed of spring metal shaped so that said spout portion lies substantially in contact 25 with the container end when moved to a position completely over the same and so as to spring to permit the spout to move over the double seam to dispensing position, said container end having raised integral inclined lugs adjacent the double 30 seam and in the path of movement of the dis-

pensing spout for raising said spout over the double seam when the spout is turned to dispensing position.

5 5. A dispensing container comprising a body portion, an end double seamed thereto, said end having a raised portion provided with a dispensing opening in its outer end, a dispensing spout permanently attached to said raised portion for rotation thereon in a fixed position relative thereto, said spout being shaped so as to lie 10 housed below and within the outer limits of the double seam when over the container end, and means for forcing said spout upwardly to extend over and in contact with the double seam when it is turned to a dispensing position. 15

6. A dispensing container comprising a body portion, an end double seamed thereto, said end having a raised portion provided with a dispensing opening in its outer end, a dispensing spout permanently attached to said raised portion for rotation thereon in a fixed position relative thereto, said spout being shaped so as to lie 20 housed below and within the outer limits of the double seam when over the container end, and raised portions on said can end for forcing said spout upwardly to extend over and in contact 25 with the double seam when it is turned to a dispensing position.
